FIG. 1

FIG. 2

FIG. 3

FIG. 4

FIG. 5

FIG. 6

FIG. 7

FIG. 8

FIG. 9

FIG. 10

FIG. 1 is a perspective view of a cigarette lighter showing my new design;

FIG. 2 is a side elevational view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a perspective view of a cigarette lighter showing a further embodiment of my new design;

FIG. 8 is a side elevational view of the embodiment shown in FIG. 7;

FIG. 9 is a front elevational view of the embodiment shown in FIG. 7;

FIG. 10 is a rear elevational view of the embodiment shown in FIG. 7; and

FIG. 11 is a bottom plan view of the embodiment shown in FIG. 7, the top plan view being similar to FIG. 5, but without a showing of the tapered sides of the first embodiment.

I claim:

The ornamental design for a cigarette lighter, substantially as shown and described.
